DESIGN FOR A MATTRESS HANDLE

Milton L. Shifman, East Orange, N. J.

Application January 4, 1941, Serial No. 97,817

Term of patent 14 years

To all whom it may concern:

Be it known that I, Milton L. Shifman, a citizen of the United States, residing at East Orange, in the county of Essex and State of New Jersey, have invented a new, original, and ornamental Design for a Mattress Handle, of which the following is a specification, reference being had to the accompanying drawing, forming part thereof.

I claim:

The ornamental design for a mattress handle, as shown.

MILTON L. SHIFMAN.
